UNITED STATES PATENT OFFICE.

JAMES ARTHUR THOMPSON, OF RUSHVILLE, ILLINOIS.

TRAY.

1,401,209.

Specification of Letters Patent. Patented Dec. 27, 1921.

Application filed September 26, 1921. Serial No. 503,332.

To all whom it may concern:

Be it known that I, JAMES ARTHUR THOMPSON, a citizen of the United States, residing at Rushville, in the county of Schuyler, 5 State of Illinois, have invented a new and useful Improvement in a Tray, of which the following is a specification.

My present invention relates to an improved tray, and has special reference to 10 the provision of a tray suitable for insertion within the crank-case and below the No. 4 or rearmost connecting rod of the motor of a Ford automobile.

Persons familiar with this portion of the 15 structure of a Ford automobile will know that the inspection plate upon the bottom of the crank-case terminates before it reaches beneath the No. 4 or rearmost cylinder, and that the crank-case beneath the 20 No. 4 cylinder is inclined downwardly and rearwardly to constitute the walls for enclosing the fly-wheel, transmission mechanism and its associated elements. The space remaining for operations or work upon the 25 No. 4 connecting rod cap is very much circumscribed, and it is quite impossible to see the work while operating upon it. As a consequence the elements for securing the cap to the connecting rod and the tool or 30 tools with which the work is being done often fall into the crank-case and slide to the lowest portion thereof from whence it is a difficult and tedious operation to recover them.

My tray is adapted to be assembled with 35 the rear edge of the inspection opening and to extend below No. 4 cylinder in such a manner that articles cannot fall into the crank-case. The tray is so shaped that the 40 motor can be turned over while it is in place for testing the adjustment of the connecting rod cap and in no way limits the space available for working around these parts. The mere presence of my tray in 45 position relieves the workman of the anxiety and trepidation of dropping an oily part or tool, and gives him sufficient assurance to quickly complete the required work. The tray is also desirable when No. 4 piston is 50 removed which is sometimes necessary.

My invention is illustrated in the accompany drawings in which—

Figure 1 is an outline side elevation of a Ford motor, a portion thereof being 55 broken away to illustrate the location and

assembly of my tray with the inspection opening in the crank-case.

Fig. 2 is a side elevation of my tray, slightly enlarged, and

Fig. 3 is a top plan of the tray somewhat further enlarged.

Similar reference characters refer to the same parts throughout the several views. The tray may be economically stamped from a suitable grade of sheet metal so as to comprise a bottom 5, oppositely disposed side-walls or upturned side edges 6, and a rear-wall or edge 7. The walls or edges 6 and 65 7 are preferably curved at their juncture with the bottom so as to facilitate the 70 cleaning and removal of the tray, and the rear-wall or edge 7 slopes rearwardly and is extended above the planes of the side-walls or edges to prevent objects falling in the tray from bouncing over and beyond it. 75 The side-walls or edges 6, when the tray is in position, conform to the walls of the crank-case, but the rear-wall or edge 7 extends upwardly adjacent the magneto.

The junctures of side-walls or edges 6 80 with rear-wall or edge 7 are curved to facilitate the manufacture of the tray by means of a stamping process. The front wall or edge 8 slopes at the sides thereof from the bottom to the height of side-walls 6, the central portions of both the bottom and the front wall being carried further forwardly or bulged, as at 9, so as not to interfere with the rotation of the crank when the connecting rod and cap are assembled therewith. 85 The bulge just mentioned shapes the forward portion of the bottom of the tray to conform with the shape of the crank-case when the tray is in operative position 90 therein.

From the line joining the forward edges of the side-walls the forward edge or wall is carried horizontally forward, as at 10, and then looped downwardly and backwardly, as at 11, and terminated in a depending vertical portion or lip 12, which for strength is folded upon itself as clearly shown in Fig. 2 of the drawings.

For the most convenient insertion of the tray, the motor should be arranged with the 105 portion of the crank between No. 3 and No. 4 connecting rods disposed horizontally. The tray is then tilted and inserted side-wise into the inspection opening and then turned 110 squarely or tilted back to horizontal posi-

tion and pressed rearwardly until the looped portion 11 engages the rear edge 13 of the inspection opening when the rear portion of the tray will fall by gravity until the bottom of the tray is in horizontal position, and the edges thereof lie closely adjacent the walls of the crank-case. To disengage the tray all that is necessary is to press the depending lips 12 rearwardly and upwardly, thereby swinging the rear portion of the tray upwardly whereupon it may be easily removed.

What I claim as new is:

1. A tray comprising bottom, side and end walls, the side and forward end walls being shaped to conform with the inner surface of the crank case of the motor of a Ford automobile when the tray is disposed horizontally therein beneath the No. 4 or rearmost cylinder, the forward end wall being extended and terminated in a depending lip whereby the tray may be swung upwardly and forwardly to permit of its removal from the crank-case.
2. A tray shaped to rest in a horizontal position between the walls of the crank-case beneath a cylinder of a motor, one edge whereof is extended, curved downwardly

and rearwardly and provided with a depending lip, whereby the tray may be swung upon its extended edge to permit of its removal from the crank-case.

3. An article of manufacture for use with a motor, the crank-case whereof is provided with an inspection opening, consisting of a tray adapted to be inserted through said opening and shaped to conform to the side walls of the crank-case when disposed horizontally within said crank case, said tray having a portion thereof produced and curved to extend through said inspection opening and back under the edge thereof.

4. As an article of manufacture, a tray comprising a bottom having upturned edges, one of said edges having a horizontally extended portion that is curved downwardly and rearwardly and provided with a depending lip, and the portion of said tray adjacent the juncture of the bottom with the extended edge being bulged outwardly whereby a recess is provided in said tray.

Signed at Rushville, county of Schuyler and State of Illinois, this 29th day of August, 1921.

JAMES ARTHUR THOMPSON.
